(57) **CLAIM**

The ornamental design for a radionuclide carrier loader, as shown and described.

DESCRIPTION

FIG. 1 is a perspective view of the lid portion of a radionuclide carrier loader shown separately for clarity of illustration showing our new design;

FIG. 2 is a perspective view of the base of a radionuclide carrier loader shown separately for clarity of illustration;

FIG. 3 is a front elevational view of the base thereof;

FIG. 4 is a front elevational view of the lid thereof;

FIG. 5 is a back elevational view of the base thereof;

FIG. 6 is a back elevational view of the lid thereof;

FIG. 7 is a left side elevational view of the lid thereof;

FIG. 8 is a left side elevational view of the base thereof;

FIG. 9 is a right side elevational view of the lid thereof;

FIG. 10 is a right side elevational view of the base thereof;

FIG. 11 is a top plan view of the lid thereof;

FIG. 12 is a top plan view of the base thereof;

FIG. 13 is a bottom plan view of the lid thereof;

FIG. 14 is a bottom plan view of the base thereof;

FIG. 15 is a perspective view of a radionuclide carrier loader shown in a closed portion showing our new design;

FIG. 16 is a front elevational view thereof;

FIG. 17 is a back elevational view thereof;

FIG. 18 is a left side elevational view thereof;

FIG. 19 is a right side elevational view thereof;

FIG. 20 is a top plan view thereof; and,

FIG. 21 is a bottom plan view of the base thereof.
